[57] CLAIM

The ornamental design for a faucet handle, as shown and described.

DESCRIPTION

FIG. 1 is a perspective view of a faucet handle showing our new design;

FIG. 2 another perspective view thereof;

FIG. 3 is a top plan view thereof;

FIG. 4 is a side elevational view thereof; and

FIG. 5 is another side elevational view thereof, with the handle rotated 60 degrees from the position shown in FIG. 4.

The broken line representation of a lavatory faucet in FIG. 1 and a single valve in FIG. 2 is for purpose of illustration only.

FIG. 2

FIG. 1

FIG. 3

FIG. 4
